UNITED STATES PATENT OFFICE.

WILHELM GOTTHILF SCHRÖDER, OF LÜBECK, GERMANY.

ARRANGEMENT FOR HOMOGENIZING LIQUIDS.

1,237,222.

Specification of Letters Patent. Patented Aug. 14, 1917.

Application filed August 26, 1916. Serial No. 117,108.

To all whom it may concern:

Be it known that I, WILHELM GOTTHILF SCHRÖDER, manufacturer, a citizen of the free town of Lübeck, in the Empire of Germany, and resident of 41 Luisenstrasse, in the said city of Lübeck, Germany, have invented new and useful Arrangements for Homogenizing Liquids, of which the following is a specification.

- 10 The present invention relates to an arrangement for homogenizing liquids, in particular milk and the like. The term "homogenizing" signifies the levigating or grinding down of liquids which would otherwise 15 not mix with each other, under a high pressure; by such grinding or levigating the said liquids are mixed in such a manner, that it will no more be possible for them to separate according to their respective specific 20 gravities. In order to attain this object the liquid to be homogenized is forced between two surfaces tightly pressed against each other, of which the one surface may rotate oppositely to the other. These homogenizing 25 surfaces generally have the form of male or female cones. The liquid was generally made to enter at the smaller radius of the homogenizer and leave it at its larger radius. When the gap between the male and the female 30 cone is equally wide at all points, the specific grinding effect will be largest at the entrance end, and be smallest at the discharge end, where the cone is of the larger radius.
- 35 With the object of avoiding this it has been suggested to employ cones which are stepped, and the gap between which can be adjusted, either by adjusting the steps in the wall of the casing, or by regulating the steps 40 of the cone. According to the present invention an emulsive effect increasing continuously from the entrance end to the discharge end is obtained, by introducing the liquid at the end of the emulsive body having 45 the larger diameter and allowing of the liquid being discharged at the end having the smaller diameter.
- In the accompanying drawing homogenizing apparatus of the hereinbefore specified novel form are exemplified. Figure 1 is a section through such an arrangement. Fig. 2 is a section through another constructional form. Fig. 3 is a section on the line B—B in Fig. 2.
- 50 In the constructional form shown in Fig. 1, a is the casing, into which the liquid to be homogenized enters at E , and which is conically shaped at b . In this female cone the homogenizer c revolves, the spindle d of which leads through a suitable stuffing gland out of the casing and has fitted to its outside end a cord pulley e , which may be driven by any suitable means, so as to rapidly rotate the cone during the homogenizing process. This rotation may, however, 55 also be produced by other means; so, for example a suitable part, attached to the cone, might be constructed in form of a turbine, or be provided with helical passages, so that the liquid running through will cause the 60 cone itself to rotate like a turbine. Between the male cone c and the female cone b a narrow gap is left, through which the liquid must pass; in order to facilitate the liquid passing from the casing a to the gap, the 65 cylindrical part of the cone is provided with notches f . The liquid flows in such a manner through the gap that the sectional area of the liquid body to be considered will decrease continuously, although the width of 70 the gap remains constant. This is obtained by the said area being in direct proportion to the product of the respective radius and the width of the gap. At the entrance of the liquid the area is $\pi r/1$, in the middle 75 $\pi r/2$ and at the discharge $\pi r/3$. At the rate at which $r/1$ is larger than $r/2$ and $r/2$ larger than $r/3$, the passage area will decrease, so that a continuously increasing 80 effect in the treatment of the material to be 85 homogenized is obtained. The cone will practically submit the material along its first part to a preliminary grinding, homogenize it along its second part, and levigate it at the discharge to a still greater fineness. 90 This is all obtained without it being necessary to readjust the apparatus, as the wear will, and particularly when the cone is 95 revolved, be equal at all points.
- For allowing of an adjustment the spindle d is journaled on a lever h pivoted in the frame g ; the free end of this lever bears against a set screw i . By adjusting this screw, therefore, the pressure in A , and the degree of fineness of the homogenization 100 may be varied.
- Obviously the same object might be attained by employing a stepped cone or some other shape of the homogenizer, the surfaces of which, in such case, need not be adjustable.
- 105 With the arrangement according to the

present invention it is essential that the cone has a sufficiently large apical angle of about 90° or more. It may even be made in form of a plate, that is to say, as a cone with an 5 apical angle of 180°.

In the constructional form according to Figs. 2 and 3 the cone is driven on its rear by turbines. As may be seen from Fig. 3, also here the liquid enters at E, acts on the 10 turbine vanes *m* and thereby causes the cone to rotate. The cone has several grooves *n*¹, *n*², *n*³ cut into it, which make a series of cone sections *c*¹, *c*², *c*³, *c*⁴ so that in each of said grooves the material which has been ground 15 along the preceding section is mixed. The cone is supported at top and bottom by a step point. The upper spindle D at the same time serves as a guide for the turbine, which must be cast in one piece with the cone.

20 I claim—

1. An arrangement for homogenizing liquids comprising a stationary body having an inverted hollow frusto-conical chamber therein, and a rotating body having a 25 frusto-conical portion fitting in but spaced slightly away from said chamber, means for adjusting the position of said rotating body relative to said chamber, means for supplying the liquid to be homogenized to the larger end of said chamber and for carrying it away from the smaller end of said chamber, and means for rotating said rotary body, substantially as described.

30 2. An arrangement for homogenizing liquids comprising a stationary body having

a cylindrical shell terminating in an inverted hollow frusto-conical chamber therein, and a rotating body having a cylindrical portion with axial slots therein, and having a frusto-conical portion fitting in but spaced slightly 40 away from said chamber, means for adjusting the position of said rotating body relative to said chamber, means for supplying the liquid to be homogenized to the larger end of said chamber and for carrying it 45 away from the smaller end of said chamber, and means for rotating said rotary body, substantially as described.

3. An arrangement for homogenizing liquids comprising a stationary and a rotating body spaced apart to leave a narrow gap between them, means for supplying the liquid to be homogenized to the larger end of the rotary body and for carrying it off 50 from the smaller end thereof, a spindle for said rotary body, means for rotating said spindle, a lever having an arm forming a journal bearing for the lower end of said spindle, and a set screw also engaging said lever for raising or lowering said spindle 55 through the desired distance, substantially as described.

In testimony, that I claim the foregoing as my invention, I have signed my name in presence of two witnesses, this 6th of June, 65 1916.

WILHELM GOTTHILF SCHRÖDER.
